FOREIGN PATENT DOCUMENTS

CN 202030525011.8 * 3/2021

Primary Examiner — Omeed Agilee(74) *Attorney, Agent, or Firm* — Sterne, Kessler, Goldstein & Fox P.L.L.C.; Charles B. Cappellari(57) **CLAIM**

The ornamental design for a receptacle holder, as shown and described.

DESCRIPTION

FIG. 1 is a top front perspective view of a receptacle holder showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the receptacle holder that form no part of the claimed design.

1 Claim, 8 Drawing Sheets(56)
